UNITED STATES PATENT OFFICE

CLAUDE DORNIER, OF FRIEDRICHSHAFEN-ON-THE-BODENSEE, GERMANY, ASSIGNOR OF
ONE-HALF TO THE FIRM DORNIER-METALLBAUTEN G. M. B. H., OF FRIEDRICHSHAFEN-ON-THE-BODENSEE, GERMANY

STUB WING OF FLYING BOATS

Application filed May 11, 1929, Serial No. 362,377, and in Germany May 14, 1928.

My invention refers to flying machines, more especially of the flying boat type and has particular reference to the stub wings or side floats attached to the hull of such flying boats.

It is an object of my invention to improve the resistivity of such stub wings against the impact of the water by providing same with an elastic protection which substantially covers part or the whole of the bottom side of these wings.

The elastic bodies serving to protect the stub wings may either be formed of any material resistive against water and possessing sufficient elasticity or may have the form of gastight resilient containers or bags filled with air or some other gas.

Such elastic protective bodies may extend all over the width of the wing or only over part thereof and may be surrounded by an elastic protective skin or may be protected against damage by resilient or resiliently mounted plates formed of non-resilient material. They may either form a separate layer on the underside of the stub wing or may be embedded therein.

In the drawings affixed to this specification and forming part thereof stub wings embodying my invention are illustrated diagrammatically by way of example.

In the drawings

Fig. 1 is a front view of a stub wing according to this invention and

Fig. 2 is a plan view, viewed from below.

Fig. 3 is a vertical section of the outer end of a stub wing having its bottom side lined with elastic bodies.

Fig. 4 is a view similar to the one shown in Fig. 3, in which an elastic body is shown to form one edge of the stub wing.

Fig. 5 is a vertical section of another modification.

Referring to the drawings and first to Figs. 1 and 2, 1 is the outer skin of the girder-like stub wing structure, 2 being the struts reinforcing same. 3 are cross-beams forming part of the stub wing structure and projecting from the underside therefrom. 4 is a large elastic body extending all over the width of the stub wing at the rear end thereof, while

5 are similar elastic bodies of smaller size, each extending over half the width of the wing. The bodies 5 covering the front portion of the wing are enclosed between an outer rim 6 and a partition 7.

In the modification illustrated in Fig. 3 elastic bodies 8, which may also be formed of wooden boards, cover the bottom side of the wing structure.

In the form shown in Fig. 4, the front portion 10 of the stub wing structure 9 affords room for the accommodation, on its underside, of an elastic body 11, the front edge of which projects beyond the front edge 65

of the wing.

In the modification illustrated in Fig. 5 the elastic bodies 12 are mounted on the underside of the stub wing 13 substantially as shown in Fig. 2. However, here resilient plates 14 are fixed at 15 to the bottom ends 70

of the cross-beams 16 and on being acted upon by the water will give way, rocking upwardly and compressing the elastic bodies, while at the same time affording protection 75

therefor.

Preferably the plates 14 are fixed to the bottom sides of the elastic bodies, which may be cushions or bags filled with air or some other gas.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. A stub wing for flying machines and an elastic protective body covering part of the bottom side of such stub wing.
2. A stub wing for flying machines and a gas-filled cushion covering part of the bottom side of such stub wing.
3. A stub wing for flying machines and a 100

plurality of elastic protective bodies covering the bottom side of such stub wing.

4. A stub wing for flying machines, an elastic protective body covering part of the bottom side of such stub wing and a resilient protective plate fixed to the bottom side of said stub wing below said protective body.

5. A stub wing for flying machines, an elastic protective body covering part of the bottom side of such stub wing and a resilient protective plate fixed to the bottom side of said stub wing and attached to the underside of said protective body.

In testimony whereof I affix my signature.

15 CLAUDE DORNIER.
